CLAIM

The ornamental design for an award trophy, as shown and described.

DESCRIPTION

FIG. 1 is a perspective view of the front, top and right side of an award trophy showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a rear elevational view thereof; and,

FIG. 7 is a perspective view of the rear, top and left side thereof shown without the medals solely for the purpose of illustrating the separability of the design components.

In the absence of surface shading, the claim is understood to be limited to the shape and configuration as shown by the outlines and to exclude all other aspects of the surface appearance.
